UNITED STATES PATENT OFFICE.

EDWARD WELLS CHADWICK, OF EDGARTOWN, MASSACHUSETTS.

VENTILATOR FOR WINDOW-SASHES.

SPECIFICATION forming part of Letters Patent No. 289,387, dated December 4, 1883.

Application filed May 22, 1883. (No model.)

To all whom it may concern:

Be it known that I, EDWARD WELLS CHADWICK, of Edgartown, in the county of Dukes, of the Commonwealth of Massachusetts, have 5 invented a new and useful Improvement in Ventilators for Window-Sashes; and I do hereby declare the same to be described in the following specification, and represented in the accompanying drawings, of which—

10 Figure 1 is an elevation, and Fig. 2 a transverse section, of a window-frame and its two sashes provided with my invention. Fig. 3 is a horizontal section of the bottom bar of the lower sash. Fig. 4 is a top view, Fig. 5 a 15 horizontal section, Fig. 6 a transverse section, and Figs. 7 and 8 opposite side views, of the ventilator separate from the sashes.

This ventilator is to be applied to one or each of the sashes A and B, it being adapted 20 to the upper bar of the upper sash and the lower bar of the lower sash. It consists of a foraminous plate, C, a perforated plate, D, a perforated slide or valve, E, a spiral spring, F, and a knob, G, arranged and combined as 25 represented. The valve E is a plate adapted to slide in guides *a* against the rear face of the plate D, which has in it a series of holes, *b*, arranged at equal distances apart and corresponding in number and size and distances 30 apart with another such series of holes, *c*, made through the valve. The shank *d* of the knob G extends through a slot, *e*, made in the foraminous plate C, lengthwise thereof, and is fastened to the valve. The said shank is circumscribed by the spiral spring F, which at 35 one end bears against the plate C and at the other against the valve, in order to force the latter closely to its seat. The plate C is fixed or secured to the sash-bar on its inner side, 40 and the plate D is fixed or secured to such sash-bar on its outer side, and between the two

plates there is a slot or opening, H, through the sash-bar, such opening having a vertical section as wide as the plate D and a length nearly equal to that of such plate, the same 45 being to admit of the valve being moved to cover or uncover the openings in the plate D, and to allow air passing into and through such openings to freely pass to and through the openings of the plate C. 50

To the knob of the ventilator of the upper sash two cords, *g g'*, provided with tassels, may be affixed, and lead in opposite directions from the knob to and through eyes *h h* in the sash near its upper corners, such cords being 55 for operating the valve. By pulling on one cord the valve will be moved in one direction, and by pulling on the other cord such cord may be moved the opposite way.

By means of the ventilators in the two sashes 60 a room may be ventilated by currents of fresh air let into it through the lower sash, the vitiated or heated air escaping through the ventilator of the upper sash.

I claim—

1. The ventilator, substantially as described, consisting of the foraminous plate C, perforated plate D, perforated slide or valve E, the knob G, and the spiral spring F, arranged and adapted essentially and for application to a 70 window-sash, in manner as set forth. 65

2. The window-sash having in its bar a slot, H, in combination with a ventilator, substantially as described, applied to such slot, such ventilator consisting of the perforated plate D, 75 foraminous plate C, perforated slide or valve E, the knob G, and the spiral spring F, arranged and adapted essentially as set forth.

EDWARD WELLS CHADWICK.
